RADIATOR

Louis D. Waldron, Arlington, Mass.

Application June 2, 1948, Serial No. 30,702

5 Claims. (Cl. 257—262.18)

1

This invention relates to radiators and has for an object to produce radiators of the fin type but in which the fins can be applied to pipes already installed, thereby to increase the radiation without requiring removal of piping or substitution of equipment. To this end increased radiation surface is produced by the use of sheet fin material so formed and arranged that it can be applied to pipes already installed.

The radiation material may thus comprise sheet metal bent on itself and so cut out at the bend as to permit it to be placed in position on the pipe by a backward lateral motion, after which it may be secured by key means which engage the fin material at one side of the bend and on the opposite side against the pipe opposite to the face at which the fin material was applied. If desired, the key itself may be so formed as to facilitate radiation.

For a complete understanding of this invention, reference may be had to the accompanying drawings in which

Figure 1 is a perspective view of a strip of sheet metal cut in a manner to permit it to be bent to form the radiation fins and applied to the pipe.

Figure 2 is a perspective view showing the strip of Figure 1 bent alternately in opposite directions to form a metal fin structure for application to a pipe.

Figure 3 is a top plan view of the fin material of Figure 2 applied to a pipe.

Figure 4 is a detail section to a larger scale on line 4—4 of Figure 3.

Figure 5 is a view similar to Figure 3, but showing the fin material opened up somewhat from the showing of Figure 3.

Figure 6 is a view similar to Figure 4, but showing a modification.

Figure 7 is a fragmentary perspective view showing the upper end portion of one of the keys and related parts.

Figure 8 is a view similar to Figure 3, but showing a modification.

Figure 9 is a view similar to Figure 3, but showing a modification.

Figure 10 is an end elevation of the radiator element shown in Figure 9, but to a larger scale, the position of the wedge for securing the element to a pipe being indicated in dotted lines.

Figure 11 is a sectional view on line 11—11 of Figure 10.

Figure 12 is a fragmentary perspective view showing the upper edge of the element of Figures 9 to 11, inclusive, and a locking wedge.

2

Figure 13 is a fragmentary perspective view of the same element.

Figures 14 and 15 are fragmentary perspective views similar to Figure 7, but showing modifications in the wedge structure.

Figure 16 is a side elevation showing the element of Figures 1 to 8, inclusive, in condition for shipment.

Referring first to Figures 1 and 2, there is shown a strip of heat conducting sheet material 1, such, for example, as metal, within which may be cut slots 2 spaced apart lengthwise thereof and of somewhat greater depth than width and each having rounded ends 3. The sheet material may then be bent alternately in opposite directions at about the dotted line positions 4 to form a zigzag structure as shown in Figure 2 having two series of bends at 5 and 6 arranged in substantially parallel planes. The slots 2 then form notches extending into the sheet material strip from the bends 5 and terminating in rounded extremities such that the strip may be placed over a pipe 10, as shown in Figure 4, the pipe entering the notches through the bent portions 5. If desired, also, the inner curved ends of the notches may be slit at desired close intervals as at 11 to furnish weakened tongues, which may give way under pressure exerted between the strip and the pipe tending to force the strip onto the pipe, such that these weakened portions may be deflected in one or the other direction longitudinally of the pipe, increasing the total area of contact between the pipe and the sheet material and thus acting to improve heat conductivity therebetween.

Figure 16 shows the strip with its folded portions pressed closely together, which is a form in which the sheet material may be placed for ease of shipment and which, if desired, may be made up from the uncut sheet material, whereupon the notches are cut inwardly from one side along the bends of that side, as, for example, through the bends along the side 30. When the closely folded element, such as is shown in Figure 16, is to be applied to the pipe, the adjacent layers are spread apart as shown, for example, in Figures 3 or 5.

The bent sheet may be secured to the pipe by suitable key means such as the key 14 shown in Figure 4 which is passed down on the inner side of the bends 5 bearing between the adjacent faces of the sheet material and the back face 15 of the pipe. Since the diameter of the pipe is substantially equal to the width of the notches and the notches are deeper than these widths,

the bends 5 extend beyond the pipe edge remote from the bases of the notches, this providing room for the keys to be inserted therebetween and with the strips engaging the pipe throughout approximately one half of its circumference. By hooking over the upper ends of the keys they may be held in position by gravity. The ends of the sheet metal radiation elements may be secured in position by any suitable means, as, for example, by being bent over and retained by rings 20 which may be clamped about the pipe 10.

Where the adjacent bent portions of the strip are to be spaced quite widely apart as shown in Figure 5, it is preferable that the inner ends of the notches, which may be formed by the slots 2, be elliptical in outline as illustrated in Figure 6 since the planes of the fin structure then intersect the pipe in sections of this contour. This is shown in Figure 6.

In place of employing a wire or rod 14 as the key element, key elements which may add to the radiating area may be employed, and to this end a T section key 25, as shown in Figures 6 and 7, may be employed, such a key presenting a rearwardly extending radiating fin 26 from a base flange 27 which may engage the pipe. Also, in order to facilitate securing the fin material tightly on the pipe, the keys may be tapered as shown in Figure 6, acting as wedges to force the fin material tightly against the outer face of the pipe. Where a T section key is employed, a cross pin 28 at its upper portion may serve to prevent the key from being driven too far downwardly and acting as a limit to prevent accidental detachment of the key from operative positions.

While as shown in Figures 2, 3 and 5, the fin material is formed of sheet stock bent alternately in opposite directions so that a plurality of pairs of fins are formed from a single piece, of course the fins could be individual in pairs, including one of the bends 5 and the adjacent sides of the fin material without being continuous one with the other around the bends 6 (Figure 8).

In Figures 9 to 13, a modified construction of radiator element has been illustrated, in which instead of forming the walls at the sides of the bends in zigzag, non-parallel arrangement as is shown in Figures 3 and 5, the bends 35 and 36 are formed more gradually and the portions 37 between the bends are brought into substantially parallel relation, this providing a structure such as is shown in Figure 9 where adjacent portions of the radiating fin material formed by the sheet metal are arranged substantially perpendicular to the length of the pipe 10 to which the radiator is applied.

The notches 40 which are cut inwardly through the bends along one side of the element are provided with tongues 41 at their bases, cut from the sheet material, and preferably bent so as to lie nearly at right angles to the planes of the portions 37, so that when the element is applied to the pipe and pulled tightly thereagainst by the use of wedge key elements 44, the tongues 41 are pulled into contact with the surface of the pipe 10, thus to increase the heat conductivity between the pipe and the radiating element. This wedging action tends to spring the tongues 41 into engagement with the pipe throughout substantially their full lengths and away from the slightly inclined relation which they assumed before application to the pipe. This is shown in Figure 11 where the left hand tongue 41 is slightly out of perpendicular relation to the portions 37, the tongue being pulled into substantial

perpendicular relation by engagement with the pipe as shown in the right hand illustration of the tongue.

While Figure 7 shows a cross pin 28 to limit the extent to which the wedge member 26 may be driven in wedging direction, somewhat simpler means, as, for example, cut and deflected portions of the keys, are shown in Figure 12 at 42 for the same purpose. Similarly where keys of T cross section, as shown in Figures 6 and 7 are to be used, these also may be provided with portions partly split and bent therefrom, as at 43 in Figures 14 and 15, to limit the extent to which the wedges may be driven in wedging direction by engagement with the adjacent edge of the sheet material.

From the foregoing description of certain embodiments of this invention, it should be evident to those skilled in the art that further modifications might be made without departing from its spirit or scope.

I claim:

1. In combination, a pipe, a radiator element comprising a piece of heat conductive sheet material bent on itself to form a plurality of spaced fins joined at one side by the bent portion, said piece being notched inwardly from one side through the bent portion to a depth greater than the diameter of said pipe to engage at said notch partly around said pipe, and a key bearing on said element at the inner face of the bend and engaging the opposite side of the pipe from the base of said notch for securing said element to said pipe.

2. In combination, a pipe, a radiator element comprising a piece of heat conductive sheet material bent on itself to form a plurality of spaced fins joined at one side by the bent portions, said piece being notched inwardly from one side through the bent portion to a depth greater than the diameter of said pipe to engage at said notch around a pipe extending through said notch, and a key bearing on said element at the inner face of the bend and engaging the opposite side of the pipe from the base of said notch for securing said element to said pipe, said key having a fin portion extending outwardly from said pipe to provide a radiating surface therefor.

3. In combination, a pipe, a radiator element comprising a piece of heat conductive sheet material bent on itself to form a plurality of spaced fins joined at one side by the bent portion, said piece being notched inwardly from one side through the bent portion to a depth greater than the diameter of said pipe to engage at said notch partly around said pipe, and a key bearing on said element at the inner face of the bend and engaging the opposite side of the pipe from the base of said notch for securing said element to said pipe, said key having a fin portion extending outwardly from said pipe to provide a radiating surface therefor and being tapered lengthwise to act as a wedge to tighten said sheet material piece against the surface of said pipe.

4. A radiator fin element comprising a strip of heat conducting sheet material bent on itself alternately in opposite directions, said element being notched inwardly through the bends along one side, said notches being deeper than their widths, whereby said element may be placed with its notches engaging over a pipe lying in said notches and of a diameter substantially equal to the widths of said notches and be held thereon by keys engaging with one face of said bends

and lying between the bends and the pipe on the notched side of said strip.

5. A radiator fin element comprising a strip of heat conducting sheet material bent on itself alternately in opposite directions, said element being notched inwardly through the bends along one side, said notches being deeper than their widths, whereby said element may be placed with its notches engaging over a pipe lying in said notches and of a diameter substantially equal to the widths of said notches and be held thereon by keys engaging with one face of said bends and lying between the bends and the pipe on the notched side of said strip, the bases of said notches being shaped to engage said pipes

15

throughout substantially a semi-circumference thereof.
